St. Petersburg, Fla. 33712

Filed Dec. 14, 1967, Ser. No. 9,842

Term of patent 14 years

Int. Cl. D19—02

U.S. Cl. D74—5

FIG. 1 of the drawings is an isometric view of a desk set embodying my new design;

FIG. 2 is a top view thereof,

FIG. 3 is a front elevational view thereof, and
FIG. 4 is a right side elevational view thereof.

The back and undisclosed side are plain and unornamented. The broken line showing of the pens in FIG. 1 and a cigarette lighter in FIGS. 1, 3 and 4 are merely for illustrative purposes.

I claim:

The ornamental design for a desk set, as shown and described.
